SPLITTING ATTACHMENT FOR LOOMS

Application filed July 26, 1930. Serial No. 471,023.

Our invention relates to fabric splitting attachments for looms.

In accordance with our invention, we provide a fabric splitting element which is adapted for attachment to the breast beam of the loom. This attachment embodies a generally horizontally arranged arm extending over a portion of the fabric passing to the sand roll. The cutting element is arranged beneath this generally horizontal arm to engage with the fabric and split the same and is carried by the arm. The arm extends over and covers the cutting element, thereby protecting the hands of the operator from contact with the cutting element. Inclined wings are preferably provided near the cutting element and serve to support the fabric and hold the same taut so that the cutting operation may be properly carried out. The splitting element as a whole is adjustable longitudinally of the breast beam so that the fabric may be cut into strips of any desired width and any suitable number of splitting elements may be mounted upon the breast beam depending upon the number of strips into which the fabric is to be cut.

In the accompanying drawings, forming a part of this specification, and in which like numerals are employed to designate like parts throughout the same,

Figure 1 is a side elevation of the splitting attachment embodying our invention,

Figure 2 is a horizontal section taken on line 2—2 of Figure 1, the cutting element being omitted,

Figure 3 is a plan view of the attachment, and,

Figure 4 is a perspective view of the attachment.

In the drawings, wherein for the purpose of illustration, is shown a preferred embodiment of our invention, the numeral 5 designates the usual breast beam of a conventional loom, arranged near the sand roll 6, having the fabric 7 passing over the same, and over a guide roll 8, and then passing to a cloth beam 9, to be wound thereon. The fabric is preferably woven with a longitudinal strip 10 formed by omitting some of the warps. The fabric is provided with as many of these

strips as desired, depending upon the number of longitudinal sections into which it is desired to split the fabric.

Mounted upon the breast beam 5 is a guide rail or plate 11, secured to the breast beam by screws or the like. This guide rail has a longitudinal slot 12 leading into a longitudinal recess 13. The rail also has an upstanding longitudinal rib or flange 14, as shown. The splitting attachment embodies a base or carriage 15, having a longitudinal groove 16 upon its lower side, receiving the upstanding rib or flange 14, and forming a slideable interlocking engagement therewith. The carriage 15 is provided with a plurality of transverse openings 17, receiving adjustable clamping bolts 18, having heads 19, mounted within the groove 18. The heads 19 do not have clamping engagement with the breast beam 5, so that the carriage 15 may be longitudinally adjusted upon the rail 11 and clamped in a selected adjusted position thereon, by manipulation of the bolts 18. Formed integral with the carriage or base 15 is a generally horizontal arm 20, in the form of a flat strap, having a substantial width. This arm extends over the fabric 7, as shown.

Preferably formed integral with the forward portion of the arm 20 is a depending substantially vertical shank 21, which is generally elliptical in horizontal cross section. Formed integral with the shank 21, adjacent to its lower end, are inclined fabric guiding and supporting wings 22, arranged upon opposite sides of the shank. These wings are arranged beneath the fabric and engage the split edges of the same, supporting the fabric and holding the same suitably taut so that the maximum efficiency is obtainable in the splitting operation. Formed integral with the lower end of the shank 21 and wings 22 is a forwardly inclined bracket 23, having screw-threaded openings 24, formed therein to receive clamping screws 25, arranged to be passed through two of the openings in an ordinary safety razor blade 26, constituting the cutting element. The blade 26 is arranged upon one side of the bracket 23 and contacts therewith while the upper end of

the blade extends into a slot 27, cut in one wing 22, adjacent to the shank 21.

Particular attention is called to the fact that the free or forward end of the arm or strap 20 projects over the blade or cutting element 26, covering the same longitudinally and laterally and extending laterally beyond the blade 26 for substantial distances. The arm thus serves as a guard to protect the hand 10 of the operator from contact with the blade 26.

The attachment is extremely simple, is formed of few parts, is strong, durable, and may be readily adjusted within wide limits.

15 The operation of the device is as follows: The carriage 15 is mounted upon the rail 11 and the upstanding rib 14 enters the groove or recess 16. The carriage is moved longitudinally of the rail to the selected adjusted 20 position and the bolts 18 are then screwed up and clamped to the carriage in this selected position. The inclined wings 22 engage beneath the split edges of the fabric while the blade 26 is supported in an inclined position 25 in advance of these wings to cut or split the fabric, as it is traveling in the direction of the sand roll.

It is to be understood that the form of our invention, herewith shown and described, is 30 to be taken as a preferred example of the same, and that various changes in the shape, size and arrangement of parts, may be resorted to, without departing from the spirit of our invention, or the scope of the subjoined claims.

Having thus described our invention, we claim:—

1. A cloth splitting attachment for looms, comprising a generally horizontal arm, means 40 for attaching the arm to the breast beam of the loom, a depending shank secured to the arm at a point spaced a substantial distance from its free end, inclined wings arranged upon opposite sides of the shank and secured 45 to the same near its lower end to engage beneath the split fabric, a bracket secured to the lower end of the shank and extending below the wings, and a blade secured to the bracket and arranged adjacent to the wings, the arrangement being such that the blade is covered by the free end portion of the arm.

2. A cloth splitting attachment for looms, comprising a generally horizontal arm, means for attaching the arm to the breast beam of 55 the loom to support the arm above the cloth, a depending shank secured to the arm at a point spaced a substantial distance from its free end, inclined wings arranged upon opposite sides of the shank and secured to the 60 same near its lower end to engage beneath the split fabric, a bracket secured to the lower end of the shank and extending forwardly beyond the wings, and a blade secured to the bracket and arranged adjacent to the wings, the arrangement being such that the blade is

covered by the free end portion of the arm.

3. A cloth splitting attachment for looms, comprising a generally horizontal arm, means for attaching the arm to the breast beam of the loom, a depending shank secured to the arm, wings arranged upon opposite sides of the shank and attached thereto to engage beneath the fabric, a bracket secured to the shank, and means for clamping a blade to the side of the bracket.

4. A cloth splitting attachment for looms, comprising a generally horizontal arm, means for attaching the arm to the breast beam of the loom, a depending shank secured to the arm, wings arranged upon opposite sides of the shank and attached thereto, one wing having a slot formed therein, a bracket secured to the shank and extending below the wings, a blade engaging one side of the bracket and passing into the slot, and means to clamp the blade to the bracket.

In testimony whereof we affix our signatures.

SUMTER L. CROLLEY.
DEWEY L. JONES.
